ADJUSTABLE RING BOOK

Henry T. Adams and Norman D. Nachtrieb, Chicago, Ill.; said Nachtrieb assignor to said Adams

Application March 13, 1935, Serial No. 10,917

10 Claims. (Cl. 129—24)

This invention relates to an adjustable ring-book and more particularly to metal parts therefor.

An object of the invention is to provide a ring-book in which two or three or more rings may be adjustably secured and in which the operation of the ring sections is facilitated by booster levers. A further object is to provide a metal back strip equipped with rods or wires to which ring sections are adjustably secured, the ring sections being provided with improved interlocking connections. Other specific objects and advantages will appear as the specification proceeds.

The invention is illustrated, in a preferred embodiment, by the accompanying drawing, in which—

Figure 1 is a top plan view of metal parts for a loose-leaf book embodying our invention; Fig. 2, a bottom plan view; Fig. 3, an enlarged detail sectional view, the section being taken as indicated at line 3 of Fig. 1; Fig. 4, a view similar to Fig. 3, but showing the ring sections open; Fig. 5, a detail sectional view, the section being taken as indicated at line 5 of Fig. 1; Fig. 6, a broken plan detail view of a pair of ring sections spaced apart to show their inner connecting ends; Fig. 7, a sectional view of a modified form of construction illustrating an initial step for securing a ring section to a wire; and Fig. 8, a similar view showing the connecting operation completed.

In the illustration, 10 designates a metal back strip provided with inturned spring side walls 11. The back strip 10 is provided with openings 12 through which the ring sections 13 extend.

Housed between the spring side walls 11 are the rods or wires 14 which are identical in construction. In the illustration given, each of the wires 14 is provided with in-bends 15 at three points, to which in-bends are secured the ring sections 13. One end of each wire 14 terminates near the end of the back strip 10, but the other end is extended through an opening 16 in the end wall 17 of back strip 10 and is then turned at right angles to provide a booster lever 18. Preferably, the end of the wire is flattened to provide a thumb piece 19 which, if desired, may be provided with knurling or superficial roughening 20.

Any suitable means for securing the in-bends 15 to the ring sections 13 may be employed. I prefer, however, to swage the in-bends 15 to provide flanges 21 which are received within the T-slots 22 of the ring sections 13. It will be observed from the showing in Fig. 6 that the flanges 21 taper near their ends inwardly toward

the body of the wire and this taper facilitates the threading of the flanges 21 within the T-slots 22 of the ring sections 13. The flanges 21 and T-slots 22 are so formed that when the flanges are drawn within the slots, the parts become firmly locked in the position shown in Fig. 6. However, if it is desired to remove the ring section 13 from engagement with the bend 15, this may be done by sliding the ring section laterally. On the other hand, if it is desired to form a permanent connection, the wire bend 15 may be tapped to expand the metal within the T-slot to form a permanent interlock. It will be understood that instead of employing a T-slot and corresponding flange, that a dovetail construction may be employed. If desired, the ring section 13 may be sheared or flattened on one side to provide a straight face 23, as shown in Figs. 7 and 8, the straight face being adapted to lie against the bottom of a recess 24 with which the in-bend 15 is provided. The adjacent metal 25 of the wire bend 15 is then spun about the ring section 13 to form the interlock, as shown in Fig. 8. It will be understood that while we have shown several methods of connecting the ring sections to the wire bends 15, many other suitable methods may be used.

The ring sections 13 are provided at their inner ends with suitable interlocking connections. We prefer that each ring section shall be a duplicate of the other and that the interlocking ends be identical in construction. As shown more clearly in Figs. 3, 4 and 6, the lower face of each interlocking end is bevelled as indicated by the numeral 26 while the upper face of each end is provided with a shoulder projection 27. Adjacent each shoulder 27 is a rearwardly inclined bevel 28. When the two ends are brought together, as illustrated more clearly in Figs. 3 and 4, it will be observed that the two ends meet along a line which is formed by the two beveled surfaces 26 and 28, and that the interlocking shoulders 27 maintain the ends against lateral movement. In order to bring the shoulders 27 against each other and to maintain them in this position, we have formed the inner faces of the ends with about a 5° taper, as shown more clearly in Fig. 6. This slight taper of the inner contacting faces causes the locking shoulders to remain in contact.

While we have described a particular form of interlocking end for each ring section 13 which has the advantage of causing the ring sections to oscillate about a single line point, thus reducing the frictional surface between two engaging ring sections, it will be understood that other types of

hinge connections may be employed in combination with other features of our invention.

In order to lock the free end portions of the wires firmly against the spring walls 11, and in order to adapt the metal back strip to a round back notebook, we provide the reinforcing strips or buttons 29, as shown more clearly in Figs. 2 and 5. The member 29 comprises a rounded web portion 30 which is adapted to be placed against the rounded back of the cover, and which is provided centrally with an opening 31 through which the rivet or other fastening means may be extended. The opening 31 is aligned with an opening 32 in the back strip 10 and through which also the rivet may be extended. The member 29 is also provided with depending spring arms 33 which are preferably curved inwardly at 34 to provide locking shoulders 35 adapted to engage the wires 14 and the outer free ends of the spring side walls 11.

In the operation of the device, the booster handle 18 may be raised to open the ring sections and when depressed, will close the ring sections. It will be observed that when the ring sections are closed, the booster handle lies in the same plane with the metal back strip. In the swinging movement of the ring sections, the contacting surface between two of the ring sections is the single line, as illustrated in Figs. 3 and 4. The reinforcing strips or buttons 29 may be shifted longitudinally of the strip to bring the openings 31 into alignment with the openings 32 of the back strip 10 so that the round back of the loose-leaf cover may be attached thereto by riveting. If it is desired to attach the back strip to a cover having a flat back, the buttons 29 may be readily removed from engagement with the back strip 10.

In assembling the ring sections upon the in-bends 15, the T-slots 22 of the ring sections are drawn over the tapered ends of the flanges 21, and the ring sections are then drawn toward the central wider parts of the flanges 21. This drawing operation tightens the ring sections upon the flanges 21 and gives them the desired rigidity. At any later time, if desired, the ring sections may be removed by exerting lateral pressure thereon; or, if desired, the ring sections can be permanently secured to the wires by tapping the wires adjacent the flanges 21.

While in the illustration given, we have shown the metal back strip equipped with two booster levers 18, it will be understood that one of the levers may be omitted if desired. There is a distinct advantage in having two levers not only because of the facility for operation by the user, but also as an aid to the manufacturer in securing the back strip parts to the cover of a loose-leaf book. In the latter operation, the manufacturer need not take pains to secure the back strip in a certain position with respect to the cover because with the booster-lever at both ends, it makes no difference whether the back strip be turned in one direction or in the other.

While we have shown the back strip equipped with three rings, it will be understood that two or four or more rings may be as readily employed by varying the number of in-bends 15 employed.

The foregoing detailed description has been given for clearness of understanding only, and no unnecessary limitations should be understood therefrom, but the appended claims should be construed as broadly as permissible, in view of the prior art.

We claim:

1. In a ring-book, a metal back strip provided

with spring side walls, a pair of wire members engaging said spring walls, each of said wire members being provided with at least one in-bend aligned with the corresponding in-bend of the other wire member, and ring sections, said in-bends and ring sections being equipped with means for releasably securing one to the other.

2. In a ring-book, a metal back strip provided with spring side walls, a pair of wire members engaging said side walls, each of said wire members having at least one in-bend aligned with a corresponding in-bend of the other member, ring sections, and releasable interlocking connections between said in-bends and said ring sections.

3. In a ring-book, a metal back strip provided with spring side walls, a pair of wire members engaging said side walls, each of said wire members having at least one in-bend aligned with a corresponding in-bend of the other member, ring sections, and interlocking connections between said in-bends and said ring sections, each interlocking connection providing a slot in said ring section and a flange in the corresponding wire member.

4. In a ring-book, a metal back strip provided with spring side walls, a pair of wire members engaging said side walls, each of said wire members being provided at least with one in-bend aligned with a corresponding in-bend of the other member, ring section members, and interlocking connections between the in-bends of said wire members and said ring sections, each interlocking connection comprising a flange on one member and a groove in its corresponding member.

5. In a ring-book, a metal back strip provided with spring side walls, wires engaging said side walls, each wire member having an in-bend aligned with a corresponding in-bend of the other wire member, ring sections secured to said aligned in-bends, said ring sections each having its inner end shaped to provide a line and said sections being also provided with interlocking shoulders maintaining the lines of said ring sections in contact.

6. In a ring-book, a metal back strip having spring side walls, wires engaging said side walls and provided with aligned in-bends, ring sections secured to a pair of aligned in-bends and having their inner ends in interlocking engagement, said ends being provided with interlocking shoulders having sides extending transversely of said wires, said sides being in engagement.

7. In a ring-book, a metal back strip having spring side walls, wires engaging said side walls, said wires having aligned in-bends, a pair of ring sections engaging a pair of aligned in-bends, said ring sections having their inner ends provided with interlocking vertical shoulders and having their contacting faces tapered so as to maintain the lateral faces of said shoulders in contact.

8. In a ring-book, a metal back strip having spring side walls, metal wires engaging said side walls and provided with aligned in-bends, a pair of ring sections engaging a pair of aligned in-bends, said ring sections having their inner contacting ends each shaped to present a line and said lines being in contact, said ends being provided with interlocking means for maintaining said lines together.

9. In a ring-book, a metal back strip having spring side walls, a pair of wire members engaging said spring side walls and having pairs of aligned in-bends, complementary ring sections secured to each pair of aligned in-bends, and an

attaching button equipped with arms adapted to engage said wires and the spring walls of said back strip, said attaching button being provided with a curved perforated back.

- 5 10. In a ring-book, a perforated metal back strip having spring side walls, wires engaging said side walls and provided with a pair of aligned in-bends, a pair of complementary ring sections secured to said in-bends, an attachment button re-

leasably engaging the spring walls at each end of said back strip, said buttons being provided with curved rear walls and having arms which engage and partially surround, the wires, said buttons having perforations aligned with the perforations 5 in said back strip.
